P. M. HART

GASOLINE CUT-OFF VALVE LOCKING DEVICE

Filed May 29, 1924

Inventor
Pearl M. Hart.

By *Clarance A. O'Brien*,
Attorney

Patented Sept. 1, 1925.

UNITED STATES PATENT OFFICE.

PEARL M. HART, OF CHICAGO, ILLINOIS.

GASOLINE-CUT-OFF-VALVE LOCKING DEVICE.

Application filed May 29, 1924. Serial No. 716,715.

To all whom it may concern:

Be it known that I, PEARL M. HART, a citizen of the United States, residing at Chicago, in the county of Cook and State 5 of Illinois, have invented certain new and useful Improvements in Gasoline-Cut-Off-Valve Locking Devices, of which the following is a specification.

This invention relates to locking devices 10 for gasoline cut-off valves for use on automobiles.

An object of the invention resides in providing a cut-off valve in the gasoline feed pipe to the carburetor of an automobile 15 having a rod extending axially from the valve plug to the instrument board of the vehicle, wherein the same is provided with an enlarged head having a handle extension, the head being rotatably mounted in the instrument board and containing a suitable 20 key-controlled lock operable for locking the valve in closed position to cut off the supply of gasoline to the carburetor.

A further object of the invention resides 25 in providing a locking device arranged in the extension from the plug of a controlling valve for the gasoline feed pipe of an automobile, and located in the instrument board in convenient reach of the driver, so that 30 the same may be operated to cut off the supply of gasoline to the carburetor, and locked in cut off relation at the instrument board.

The invention further comprehends other 35 objects and improvements in the details of construction and arrangement of the parts, which are more particularly pointed out in the following description and claim directed to the preferred form of the invention, it being understood, however, that various 40 changes may be made in the specific instruction and assemblage of parts within the scope of the invention as described and claimed.

In the drawing forming a part of this 45 application:

Figure 1 is a view, showing the application 50 of the invention to the instrument board and gasoline feed pipe of a suitable form of automobile.

Figure 2 is a sectional view taken on line 2-2 of Figure 1.

Figure 3 is a longitudinal sectional view 55 through the device, parts thereof being shown in elevation.

The gasoline feed pipe of an automobile is indicated at 1, which connects the tank 2

containing a supply of gasoline with the carburetor 3 in the usual and well-known manner.

A cut-off valve indicated generally at 4 is 60 interposed in the gasoline feed pipe, which as clearly indicated in Figure 1 comprises a valve body 5 having a passage therethrough for the gasoline and receiving in a transversely extending opening the tapered 65 valve plug 6 for controlling the passage through the body. One end of the plug 6 has a reduced extension 7 on which is mounted a coiled spring 8 having one end seated against a washer 9, and the other end 70 against a pin 10 mounted in the end portion of the reduced extension 7. The washer 9 is keyed in any well known manner (not shown) to the reduced extension 7 and is provided with a plurality of radially ex- 75 tended struck-out portions 11 adapted to seat in notches 12 in the valve body for holding the valve plug in either closed or opened position, through the action of the spring 8, which also serves to maintain the 80 plug 6 in liquid tight relation with the valve body 5.

The other end of the plug 6 is provided with a rod extension 13 of substantial 85 length, which extends through an opening in the instrument board 14 of the vehicle, and is rotatably mounted in a suitable plate and movably connected to said instrument board, and indicated at 15. This plate is formed with an opening 16 in the central 90 portion, and at diametrically opposite sides of which are formed slots 17, while the rear side of the plate is formed with an enlarged annular recess 18, surrounding the opening 16, the purpose of which will presently 95 appear.

The outer end of the rod 13 is enlarged 100 as indicated at 19, and is recessed as indicated at 20 to receive a suitable form of key operated locking device 21, to be housed 105 within the recess 20 for operating the locking bolt 22, slidably mounted in the transverse bore 23 in the enlarged portion 19 of said rod. The portion 19 is formed with a reduced cylindrical portion 24, which seats 110 in the opening 16 in assembled relation of the rod in the plate 14, and which is provided with diametrically opposite projections 25, which are adapted to be inserted through the slots 17 in the plate, and to 115 normally seat in the annular recess 18 of said plate, for preventing detachment of

the plug 6 from the valve body in the assembled relation of the parts. In this assembled relation, the transversely slidable bolt 22 is adapted to be projected into one of the slots 17 for locking the valve in position to cut off the supply of gasoline to the carburetor, while at the same time withdrawal of the rod is prevented from the plate 15 by the projections 25. The outer 5 end of the enlarged portion 19 of the rod is formed with a lateral projection 26 to form a handle, by which the rod and valve plug 6 may be rotated for opening and closing the valve in controlling the gasoline 10 feed. The key 27 for controlling the lock 21 is inserted in the lock through the end thereof in the manner clearly illustrated in the drawing, and in the assembled relation of the parts, the handle 26 is arranged in 15 spaced relation with respect to the instrument board 14, so that the same may be conveniently grasped for operation in opening and closing the valve.

From the foregoing description, it will 20 be clear that a relatively simple construction has been provided for locking the controlling valve for the gasoline feed to the carburetor of an automobile, which provides a lock and operating handle on the 25 instrument board of the automobile, which is conveniently operable by the driver for controlling said valve.

What I claim is:

A locking device for cut off valves positioned in the gasoline feed pipe on a motor vehicle comprising a rod extension from the plug of said valve extending through the instrument board of the vehicle, a bearing plate provided on said instrument board having an opening with an enlarged portion, said rod extension being provided with an enlarged portion rotatable in the opening of the plate and having a recess therein, a lock disposed in the recess and including a transversely movable bolt, projections provided on the enlarged portion of the rod extending laterally therefrom at right angles to the bolt of the lock, and adapted to be disposed in the enlarged portion of the opening, said opening provided with notches adapted to be engaged by the bolt for preventing rotation of the rod at which time the projections will prevent the longitudinal movement of the rod through the opening, whereby when the bolt is unlocked and moved out of the notches, the rod may be rotated to bring the projections in registry with the notches to allow the longitudinal movement of the rod through the opening for withdrawal purposes or the like, and a crank on the end of the rod.

In testimony whereof I affix my signature.

PEARL M. HART.
